JOHN EMERY HARRIMAN, JR., OF BROOKLINE, MASSACHUSETTS; JULIA L. HARRIMAN, ADMINISTRATRIX OF SAID JOHN EMERY HARRIMAN, JR., DECEASED, ASSIGNOR TO FRANK B. DOLE, OF BROOKLINE, MASSACHUSETTS.

EDGE-SETTING MACHINE.

1,208,552.

Specification of Letters Patent. Patented Dec. 12, 1916.

Application filed November 9, 1909, Serial No. 527,085. Renewed May 3, 1916. Serial No. 95,253.

To all whom it may concern:

Be it known that I, JOHN EMERY HARRIMAN, Jr., of Brookline, in the county of Norfolk and State of Massachusetts, have 5 invented certain new and useful Improvements in Edge-Setting Machines, of which the following is a specification.

This invention relates to machines for setting or burnishing the sole edges of boots 10 and shoes.

It has for its object to combine in a single machine the means for applying the preliminary dressing or dressings to the sole edge and a tool or tools for setting the 15 edges, together with provisions for drying the dressing where the same is a liquid, and means for enabling the shoe to be held and shifted from one position to another so that it may receive the dressing and be subjected 20 to the action of the setting tool without requiring intermediate handling.

A further object is to provide holding means in connection with such a machine which will cause the sole edge to be pressed 25 against the setting tool or tools with sufficient force for the purpose desired, and without requiring much expenditure of energy on the part of the operator. In other words it has hitherto been necessary 30 for workmen operating edge-setting machines to exert a comparatively great upward pressure while holding the sole edge of a shoe against the setting tool in order that satisfactory work may be done, and 35 this has always been considered as one of the most laborious and strength-taxing operations in the entire shoe factory, so that only very strong men are able to perform it, and even such men are unable to continue at 40 such work for any great length of time. Accordingly, in carrying out the other objects of my invention, I have provided a holder for the shoe which is so weighted or 45 acted upon by spring or other pressure, that it more than counter-balances the weight of the shoe, and exerts a resultant upward pressure thereon.

In this connection it has been my object 50 to provide a holder which will accomplish such result and also serve to carry the shoe directly from the positions in which it receives one or more coatings of a dressing or

of different dressings into the position where it is acted upon by the edge-setting tool.

In the accompanying drawings, Figure 1 55 shows an elevation of a machine embodying the principles of my invention in which is shown one mode of carrying the invention into effect. Fig. 2 is a side elevation of the machine as seen from the right of Fig. 1. Fig. 3 is a plan view of the machine. Fig. 4 is an elevation of the shoe-holding device or support as seen from the right of Fig. 1, showing diametrically different positions which may be given to a shoe held 60 thereby. Fig. 5 is a sectional view and Fig. 6 an elevation of a form of applying dressing to the edge of a shoe sole adapted to be used in connection with this machine.

The same reference characters indicate the 70 same parts in all the figures.

Referring to the drawings the reference numeral 1 represents the column of an edge-setting machine rising from a base or pedestal 2. On the upper part of the column is an edge-setting tool 3, which may be of any suitable character and is preferably any one of the edge-setting or burnishing tools at present in common use. For the purpose of illustration I have shown the 80 tool as being a block carried by a reciprocating holder 4, which is pivoted to a bracket 5, although it is to be understood that any other type of tool suitable for the purpose may be employed. In the embodiment 85 shown, the bracket 5 hangs from a table 6, secured upon the top of the machine and the setting tool holder is oscillated by a lever 7 connected by a link 8 with a crank stud 9 on a shaft 10 which is journaled in a 90 bearing 11, rising from the table 6. Two or more tools 3 and 3^a respectively may be mounted upon the holder 4 in interchangeable relation so that either may be used for acting on different parts of the sole, such 95 as the fore part of the sole and the shank respectively.

One of the principal objects of my invention, as before stated, is to provide means for applying dressings such as gum, ink, 100 blacking or other dressing to the edge of the sole before the same is acted upon by the burnishing tool. For this purpose I provide a tank or tanks 12, 13, which are con-

veniently supported upon brackets 14 above the table 6, and have outlet pipes 15, 16 respectively. These pipes, as shown in Figs. 1 and 2, extend downward to approximately 5 the level of the setting tools to enable a shoe to be moved from one to the other in a horizontal path. As it is common to apply first a gum to the edge of the sole, and then, after the latter is dried, to apply black- 10 ing or ink before the sole is set by the burnishing tool, I find it convenient to supply a tank 12 with gum, and a tank 13 with the blacking or other dressing, and to ar- 15 range the outlet pipes 15 and 16 as shown best in Fig. 3, so that a shoe may be held in position to receive gum issuing from the nozzle of the pipe 15, and then be inked by the dressing issuing from the nozzle of the pipe 16 in succession before being presented 20 to the setting tool.

In order that the dressings may be applied with some force and fully distributed, and in order further to dry the dressings where the same are in liquid form, I find it 25 convenient to blow the dressings in an atomized condition against the sole edge by compressed air which may be heated if desired to secure more rapid drying, and further to direct an additional current of air, heated if 30 desired, upon the sole, so that it blows against the dressing as soon as it is applied and dries the same almost instantly. For this purpose I provide a compressed air tank 17 which is placed at any desired point and 35 may conveniently be mounted beside the dressing tanks upon brackets 18. A pipe 19 issues from the air tank and has branches 20 and 21 extending to the outlet pipes of the dressing tanks respectively, while from each 40 of these branches extend pipes 22, 23 and 24, 25 respectively. The pipes 22, 24 lie beside the outlet pipes 15 and 16 of the dressing tanks respectively and blow the dressing therefrom in a finely divided condition with 45 an action similar to that of the ordinary well-known atomizer. The other pipes 23 and 25 respectively are provided for directing a stream of air upon the edge of the sole after the dressing has been applied thereto, 50 in order to dry the same.

The shoe is supported by a device which is capable of movement so that the edge of the sole of the shoe may be presented successively to each of the various instrumentalities which act upon it, that is, to the outlets for the dressing and to the burnishing tool, and also with provisions for moving the shoe while adjacent to any one of these instrumentalities so that the entire extent 55 of its sole edge is presented thereto. The holder therefore forms an important element of my invention in combination with the machine as a whole. A suitable embodiment of the holder is the one here illustrated 60 which consists of a rod or bar 26 having a

pocket or saddle 27 to receive the shoe and mounted for universal movement. That is, the rod is mounted so that the shoe-holding portion thereof may be raised or lowered, moved laterally to one side or the other, 70 moved in or out, and rotated about its axis. To permit of these motions it is supported by a bracket 28 projecting from the column 1 and having an aperture through which the rod extends. This aperture is a sufficient 75 amount greater in diameter than the rod to permit of lateral and vertical movement of the rod to the desired extent, and on the rod on each side of the bracket are mounted collars 29 and springs 30, which latter act 80 against fixed abutment shoulders 31 on the rod. The action of these springs is to tend to hold the rod in a position of equilibrium wherein it extends perpendicular to the bracket 28, while at the same time permitting 85 the desired swing of the rod to take place, and also permitting the rod to be moved endwise. Any other form of universal connection between the rod and the supporting bracket might be employed, but 90 I have found this suitable for the purpose, as it permits the desired character and extent of movements and is simple and of low cost.

The pocket 27 which embraces the shoe is 95 conveniently a metallic shell of a size sufficient to receive the heel and the counter of the shoe, and preferably lined with felt, rubber or other soft substance to avoid injuring the leather of the shoe. Preferably also the 100 pocket member has spring arms 32 extending a considerable distance toward the toe of the shoe to embrace the fore part of the latter and assist in holding it in place. The holder also has a bracket 33 secured to the 105 rod and projecting in such a position that the sole of the shoe may rest against it, leaving the edges of the sole exposed between the bracket and the spring arms 32. After being placed in the holder the shoe is secured 110 by clamping means such as that shown in Figs. 1 and 4, consisting of an angular bar 34 against which the tread surface of the heel is adapted to bear, and the end of which is carried across the rest of the heel 115 and provided with a lip 35 which may be formed with teeth or a serration as shown in Fig. 4. This angular bar serves as a clamp which is forced against the breast of the heel by a cam lever 36 having a handle 120 37. The clamp is engaged with a block 38 adjustably mounted upon the cam lever and controlled by adjusting screws or bolts 39 by which it may be regulated to shoe heels of different sizes. The proportions of the 125 parts and adjustment are such that when the clamp is tightly held against the breast of the heel by the cam lever, the handle 37 of the latter extends downward from the holder. A second handle 40 extends out- 130

wardly form the holder and both handles together serve as grips by which the necessary movements may be given to the holder to present all parts of the sole edge to the 5 various edge-setting or treating instrumentalities in turn. The handle 40 extends out from the end of the shoe support nearly in line with the rod 26, but preferably somewhat offset therefrom to assist in turning 10 the holder about the axis of the rod.

As previously stated, the edge-setting operation is an extremely laborious and trying one for the operator, as it involves pressing the shoe upward with great force against 15 the setting tool. One of my objects has been therefore to make the shoe holder with provisions for exerting an upward pressure on the shoe to relieve the operator of this exceedingly difficult and trying work. For 20 this purpose I arrange the rod 26 so that it extends a considerable distance beyond the supporting bracket 28 and provide means for exerting a sufficiently powerful downward pressure on this projecting end to over- 25 balance the weight of the shoe and holder and to exert sufficient upward pressure on the latter to relieve the operator of the necessity of using his own strength to any great degree for the purpose of pressing the 30 sole edge against the setting iron. This means may be a weight 41 or spring 42 or both as here shown. This weight may be attached to the rod in any convenient way such as by screwing it upon the threaded ex- 35 tremity of the rod as here shown. The rod also has an angular arm 43 extending downward, to which a weight 44 is connected in the same manner, and also a spring 45 if desired. This weight supplements the weight 40 41 in pressing the shoe upwardly and also tends to hold the latter in a vertical position with its toe pointing upward, thus assisting the operator when the side edges of the sole are presented to the setting tools.

45 In operating the machine the shoe holder is first swung into the position illustrated in the drawings when the edge of the shoe sole is presented to the outlet nozzle of the pipe 15, from which a dressing such as a gum is 50 expelled. The longitudinal movement of the shoe holder permits the latter to be shifted from the position it occupies when the shoe is applied thereto into the position for presenting the shoe to the nozzle. The 55 handles 37 and 40 being grasped, the holder is oscillated about its own axis and at the same time raised and lowered to the extent necessary for carrying the entire extent of the sole edge past the nozzle to receive the 60 dressing. This dressing is evenly distributed over the entire edge and is immediately or quickly dried by the air issuing from the tube 23. The dressing is prevented from flowing over and soiling the bottom of the 65 shoe sole or the upper leather by guards 46

and 47 which flank the nozzle of the pipe 15 and are separated by a width just sufficient to admit the shoe sole. These guards are preferably flexibly or yieldingly mounted so as to admit the sole edges between them, and 70 to embrace such edges closely. After the first dressing has been applied to the shoe, the holder is swung radially in a path indicated by the line of arrows in Fig. 3, until the shoe is presented to the setting tool and 75 the first dressing is set, then the shoe is carried back to the nozzle of the outlet pipe 16, from which ink, blacking or other dressing issues. This dressing is also forced out by 80 a jet of air from the pipe 24 and is dried by 85 air issued from the pipe 25. The nozzle of this pipe as well as of the other is provided with guards 46 and 47. As an auxiliary drying means I provide a nozzle 48 extending along the sole rest 33 of the holder, and having a number of apertures through which air, heated if desired, is blown against the sole near the edges thereof. This nozzle is fed by a pipe 49 which is carried along the rod 26 of the shoe holder and is connected 90 in any desired way with the air tank 17. The shoe holder is finally swung so as to present the edge of the sole to the action of the burnishing tools 3 or 3^a for a final setting, and as before the holder is rotated about its 95 own axis, and at the same time moved laterally and vertically to present the entire extent of the sole edge to the tools. In this operation, as also in the gumming and inking stages, the weights or springs hold the 100 shoe upwardly with considerable force and relieve the operator of any effort other than that necessary for swinging and turning the shoe.

Mention has been made of the fact that 105 the air for applying and drying the dressing may be heated. Means for thus heating the air is illustrated in Fig. 2 which consists of a gas jet 50 from which a flame issues beneath the air tank 17 and the outlet therefrom. Another jet 51 is provided for heating the burnishing tool in the usual manner. The discharge of dressing and air from the various tanks is controlled by valves and treadles. The outlet pipe 15 for the first dressing has a valve 52 which is connected by a link 53 with a treadle 54. The branch or pipe 20 also has a valve 55 having an operating arm 56 connected by a link 57 of the treadle 58 beside the treadle 54. These 110 treadles are placed close together so that if desired they may be depressed by the foot of the operator at one and the same time, or they may be separately depressed. While 115 the shoe is held near the nozzle of the pipe 15, either or both of these treadles are depressed and the dressing or air or both are permitted to flow against the edge of the sole. Likewise the outlet pipe 16 and the air pipe 21 have valves 59 and 60 respec- 120 125 130

tively which are connected with treads 61 and 62 by rods 63, 64 and operating arms 65, 66 respectively. These treads 61 and 62 may be operated in the same manner as those 5 last described.

An alternative mode of applying the liquid dressing is illustrated in Figs. 5 and 6. Here the applying means is a circular brush 67 mounted to revolve about a tube 68 which 10 leads from the tank of dressing. On the hub of the brush is mounted an air turbine 69 which is rotated by a blast of air issuing from the pipe 70 which leads from the air tank 17. The dressing issues from the pipe 15 68 through a line of orifices 71, either under its own head, or under pressure of air introduced either into the tank of the dressing, or into the pipe 68. The centrifugal action of the brush and the force of the air throw 20 the dressing outward and the brush applies it to the edge of the sole. The brush is entirely surrounded by a casing 72 which has an opening sufficient to admit the edge of 25 the sole. The casing on one side of the opening serves as a shield to prevent the dressing from flowing on the upper leather of the shoe and a second shield 73 is applied to prevent the dressing from flowing over the bottom of the sole. The air, after driving 30 the turbine issues from the exhaust 74, which is so arranged as to direct the air against the edge of the sole for the purpose of drying the dressing.

This invention is a means of effecting a 35 comparatively great saving in the cost of shoe-making, as it enables the whole process of treating the edges of the shoe soles, including the applying of different dressings thereto and burnishing the edges to be completed in a single operation. It has hitherto been the practice to apply first a gum to the sole edges by hand by means of a brush, to place the shoe in a rack to dry and then set the edges by presenting the shoe to an 40 edge-setting machine, after which one or more coatings of ink or other dressing are applied to the sole also by hand, and such coat or coats must be permitted to dry before the shoe is presented to the edge setter 45 for the final setting operation. This involves four separate handlings of the shoe and at least two drying periods with a corresponding loss of time, and the services of two employees, to wit., an operator of the 50 edge-setting machine and a helper, who is usually a boy, and whose duty it is to apply the gum and blacking or other dressing to the sole edges and place the shoes upon a rack where the dressing may dry and from 55 which the shoes may be taken by the operator of the machine. That is, each setting machine requires the services of two operatives and the shoes have to be handled first by the helper who applies the gum, second 60 by the setter who operates the edge-setting

machine and burnishes the gum into the edge of the sole, third by the helper, who next takes the shoe and applies the blacking or other dressing, and fourth by the operator of the setting machine who gives the 65 sole edge the final set. If additional coats of dressing are applied the shoe must be handled a correspondingly greater number of times, each followed by the necessary period for drying. Incidentally it involves 70 also the danger of injuring the shoe by careless applying of the dressing, in which the dressing may be smeared over the upper leather or the bottom of the sole, or may run thereover or drip upon shoes placed in the 75 lower part of the rack in case an excess of the dressing is applied. There is danger also of the operators soiling the shoes by handling them when their hands are wet with the dressing. Many shoes are either 80 entirely spoiled or their value reduced by the carelessness in applying the dressing, or handling them, by virtue of which the uppers become smeared with the gum or other dressing. This causes otherwise high grade 85 shoes to become unsalable at their proper price and to be classified in inferior grades. 90

By my invention all danger of spoiling a shoe by improper application of dressing is eliminated and these several operations 95 involved in finishing the sole edges are commenced and completed in a single continuous act of one operator, without rehandling, and without loss of time in allowing the dressing to dry. This is due to the fact that 100 the dressing is dried immediately after its application. Also the labor cost is reduced, because one operator can attend to the entire treatment of the sole edges in but little more than the time required for the setting or burnishing of the edges. The operator of the edge-setting machine while handling the shoe but once can present the shoe in turn to the gumming device, the setting tool, the inking device, and the setting tool again, and this as many times as may be required to give the desired finish to the edge of the sole. The drying of the dressings is effected immediately by the means provided 105 for that purpose as hereinbefore described and thus the element of time lost while waiting for the dressings to dry is eliminated. At the same time the danger of spoiling shoes by careless application of the dressing and smearing the same or allowing it to drip on the upper leather is avoided on account of the character of the dressing-applying means before described. The cost of the edge-setting part of the manufacture of 110 a shoe is thereby materially decreased by saving the wages of the assistant and the time of the setter, while the loss due to spoiling the shoes by dressing smeared over the upper leather is wholly saved. In passing 115 it may be noted that the dressings which are 120

125 130

applied to the sole edges of shoes are compounded for the purpose of being as nearly indelible as possible, so that as a result it is almost impossible and in some cases it is absolutely impossible to remove stains caused by applying these dressings to the upper leather. At the same time the work is made lighter and less injurious for the operator on account of the aid which is given by the shoe-holder in pressing the edges of the sole against the setting tool.

All the elements of the combination are contained in the single united machine, including the tanks for the air and dressing and the setting tool, which are mounted upon the top of the machine, and the driving apparatus for both driving the tool and compressing the air which is contained in the pedestal of the machine. The means for driving the burnishing tool is a belt 75 which passes over a pulley 76 upon the shaft 10 and is driven by a pulley 77 on a counter-shaft 78, mounted in the pedestal 2 which is driven by a belt 79. This counter-shaft also serves to compress the air, as it carries a crank pin 80 which operates the piston of an air pump 81. The latter discharges into a reservoir 82, from which the air is conducted to the tank 17 by a pipe 83.

I claim,—

1. The combination in an edge-setting machine for boots and shoes, of gum-applying means, inking means, an edge-setting tool, and a shoe-holder mounted with capability of moving the shoe edge in a path substantially coincident with said means and tool, whereby to present it in succession to the action of said means and tool.

2. An edge-setting machine comprising means for applying a dressing to the edge of a shoe and drying such dressing, an edge-setting tool, and a shoe-holder movable in such a manner as to bring the shoe to said applying means and tool, and movable also to subject the entire extent of the sole edge to the action of said means and tool.

3. The combination in a machine for treating and setting the edges of shoe soles of instrumentalities for applying dressing, a burnishing tool, a shoe holder movable bodily to carry a shoe from proximity to the dressing-applying means to a position where it may be acted upon by said burnishing tool, and means for causing an upward pressure to be automatically exerted upon a shoe carried by said holder while the shoe is acted upon.

4. A sole edge-treating machine comprising a container for liquid dressing having an outlet, means for blowing dressing from said outlet, means for causing a stream of air to issue close to said outlet, whereby the dressing may be applied to the edge of a sole and immediately dried, a burnishing tool and a shoe holder, the latter being movable

in a path from said outlet to said burnishing tool, whereby to carry a shoe from one to the other.

5. A machine of the character described comprising a base, an edge-setting tool supported by said base, means for imparting a rapid movement to said tool, a container for dressing also mounted upon said base and having an outlet, means for conducting air into proximity to said outlet and causing the air to blow the dressing therefrom, and a shoe holder also mounted upon said base and movable relatively thereto in such manner as to present the edge of a sole to the air and dressing issuing from said outlet, and also to present the sole edge to said burnishing tool.

6. In an edge-setting machine the combination of a setting tool and a shoe holder, said holder being mounted with provision for movement about three axes perpendicular to each other and also movement longitudinally of one of said axes, whereby the entire extent of the edge of a shoe sole may be presented to said setting tool.

7. An edge-setting machine comprising a setting tool, a shoe holder comprising a bar movable rotatively about its own axis and also in all directions perpendicular to its length, having provisions for grasping a shoe so that the sole thereof is approximately perpendicular to the length of the bar, supporting the shoe beneath said tool, and means for causing said holder to exert an upward pressure on the shoe to force the latter into engagement with the setting tool.

8. An edge-setting machine comprising a support, an edge-setting tool carried thereby, means for conducting dressing to a point adjacent to said tool, means for conducting air to the point of emission of the dressing whereby the shoe may be held so as to receive dressing upon the edge of its sole, and to have such dressing dried by a current of air, and a holder for the shoe movable in a path from the point of emission of the dressing, whereby the shoe may be transferred from such point to said tool in one operation.

9. An edge-setting machine comprising a burnishing tool, means for conducting dressing to a point adjacent to said tool, a valve controlling the emission of dressing from said conducting means, an air conduit having an outlet beside the emission point of said dressing-conducting means, a valve in said air conduit, and treadles adapted to be actuated by the foot of the operator for controlling said valves.

10. An edge-setting machine comprising a setting tool, a conduit for dressing having an outlet near said tool, a shoe holder movable to place a shoe held thereby with the edge of its sole respectively close to the emission point of said conduit and to the edge-setting

6
tool, said holder being movable by the hand of the operator of the machine, and means controlled by the foot of the operator for governing the flow of dressing from said conduit.

11. An edge-setting machine comprising a setting tool, a conduit for dressing having an outlet near said tool, an air duct having an outlet closely adjacent to that of said dressing conduit, valves controlling the flow of dressing and air from said conduit and duct respectively, a shoe holder movable under the guidance of the hand of the operator for pressing a shoe with its sole edges respectively adjacent to said conduit and air duct outlets and to said tool, and foot-operated means for opening said valves.

12. An edge-setting machine comprising a setting tool, a conduit for dressing having an outlet near said tool, an air duct having an outlet closely adjacent to that of said dressing conduit, valves controlling the flow of dressing and air from said conduit and duct respectively, a shoe holder movable under the guidance of the hand of the operator for pressing a shoe with its sole edges respectively adjacent to said conduit and air duct outlets and to said tool, and foot-operated means for opening said valves, said foot-operated valve opening means being arranged beside one another for operation either conjointly or independently by the foot of the operator.

13. In an edge-setting machine a shoe holder having means for grasping a shoe, a setting tool and a support for said holder with respect to which the latter is movable so as to carry the shoe sidewise, endwise, about an axis transverse to the length of the shoe, and longitudinally of such axis.

14. In an edge-setting machine in combination with a standard or base in such machine and a setting tool carried thereby, a bracket upon said standard or base, a shoe holder extending from said bracket and passing through an aperture therein so as to be movable rotarily about its own axis, longitudinally of its axis, and laterally in all directions transverse to said axis, and means upon said holder for securing a shoe thereto in such manner as to extend transversely of the axis of the holder.

15. In an edge-setting machine, a setting tool, means for giving said tool a rapid movement, a shoe holder, consisting of a rod or bar mounted with provisions for movement in all directions, a pocket or shell member carried by said rod adapted to receive the rear part of a shoe, a sole rest extending transversely of the length of the holder, against which the bottom of a shoe projecting from said pocket is adapted to rest, a clamp arranged to bear against the breast of a shoe heel and secure the same in said pocket, and means acting on said shoe-

holder with a tendency to press the shoe-gripping portion thereof toward the setting tool.

16. In an edge-setting machine, a setting tool, means for giving said tool a rapid movement, a shoe holder consisting of a laterally projecting arm, mounted with provision for moving laterally in all directions, and rotarily about its own axis, a pocket on said arm adapted to receive the counter of a shoe, a clamp opposed to the back of said pocket adapted to engage the breast of the heel of a shoe placed in said pocket, a cam lever associated with said clamp and bearing against the rear portion of said pocket for forcing the clamp against the breast of the heel, a sole support against which the bottom of a shoe so held is adapted to rest, and arms projecting from said pocket for yieldingly grasping the sides of the shoe.

85
17. In an edge-setting machine a setting tool, a laterally projecting movable arm, shoe-holding means arranged to hold a shoe beneath said tool and so that the shoe projects transversely of said arm, a handle on the end of said arm beyond said shoe-grasping means, a clamp forming part of said shoe-grasping means arranged to bear against the breast of a shoe heel, and a cam lever for operating said clamp having a handle whereby it may be operated arranged at an angle to said first-named handle whereby both handles may coöperate when grasped by the hands of the operator in moving said arm and the shoe carried thereby.

96
18. In an edge-setting machine a setting tool, means for imparting a rapid movement thereto, a shoe holder consisting of an arm mounted with provisions for rotation about its own axis and for movements transverse to said axis, means on said arm for grasping the shoe, and holding the same beneath the setting tool, means associated with said arm for exerting an upward pressure on the portion thereof which carries the shoe to press the edge of the sole against the tool, and means tending to retain said arm in such a position that the shoe carried thereby projects upwardly therefrom.

105
110
115
120
125
130
19. In an edge-setting machine, a setting tool, a shoe holder, consisting of an arm mounted with provisions for rotation about its own axis and movements in all directions transverse to said axis, shoe-grasping means associated with said arm so arranged as to hold the shoe extending from the arm in a direction approximately perpendicular thereto and beneath said setting tool, a lateral extension upon said arm on the opposite side of its axis from the shoe-grasping means, and means acting yieldingly upon said extension tending to retain said shoe-grasping means in a direction such that it extends upwardly from the arm.

20. In an edge-setting machine the combination of a setting tool, a conduit for liquid dressing having an outlet beside said tool, a shoe holder having means for grasping a
5 shoe and movable to bring the shoe respectively to the outlet of said conduit and to said tool, an air conduit arranged to discharge close to the outlet of said dressing conduit to dry the dressing deposited from
10 the conduit upon the edge of the shoe sole, and air-conducting means connected to said shoe holder and arranged to discharge close to the edges of the sole of a shoe carried thereby.
15 21. The combination in an edge-setting machine, of a setting tool, an apparatus ad-
- jaacent to said tool for applying dressing, a shoe-holder including a sole rest mounted to hold a sole in a manner permitting its edge to be presented to said tool and to said apparatus, an air nozzle connected to said rest having outlets arranged to discharge air in proximity to the sole of a shoe engaged therewith to dry the dressing, and means for conducting air to said nozzle. 20
